UNITED STATES PATENT OFFICE.

ROYAL D. TOMLINSON, OF MILWAUKEE, WISCONSIN, ASSIGNOR TO ALLIS-CHALMERS COMPANY, OF MILWAUKEE, WISCONSIN, A CORPORATION OF NEW JERSEY.

CONDENSER.

No. 919,265.

Specification of Letters Patent.

Patented April 20, 1909.

Application filed July 25, 1907. Serial No. 385,422.

To all whom it may concern:

Be it known that I, ROYAL D. TOMLINSON, a citizen of the United States, residing at Milwaukee, in the county of Milwaukee and 5 State of Wisconsin, have invented a certain new and useful Condenser, of which the following is a specification.

This invention relates to condensers and 10 specifically to a specific construction of means for withdrawing air and uncondensable gases from the body of a barometric or jet condenser by the action of the water flowing out through the tail pipe.

It has heretofore been proposed to remove 15 the air and uncondensable gases which collect in the body of a jet or barometric condenser by means of aspirating devices acted upon by the water flowing out from the condenser body through the tail pipe. Ordinarily the air and gases in the body of such a condenser are in an extremely attenuated or rarefied condition so that a limit is easily reached, beyond which limit it is almost impossible for any ejector arrangement to further remove the attenuated air and gases. 25

This invention is designed to establish a zone of high vacuum, the vacuum being maintained in said zone by the action of the water flowing out through the tail pipe, and 30 this zone is in free communication with the interior of the body of the condenser, preferably at some point or points where a tendency exists for the air and gases to pocket or collect.

35 Specifically this invention comprises a structure of condenser and tail pipe of such a character that the water flowing through the tail pipe will form the well known *vena contracta* and placing the space about this 40 *vena contracta* in communication with the interior of the condenser body.

Referring to the drawings which accompany this specification and form a part thereof, and on which the same reference characters are used to designate the same elements wherever they may appear in each of the several views, and which illustrate embodiments of this invention,—Figure 1 illustrates a jet or barometric condenser, in elevation and 45 partly in section, with this invention applied thereto. Figs. 2 and 3 illustrate similar views showing modifications.

Referring to the drawings, the numeral 1 designates a condenser body provided with the steam inlet 2, the water injection pipe 3, 55 the overflow pipe 4, the tail pipe 5, the umbrella 6, the spray controlling valve 7 adapted to be actuated from the exterior of the condenser body by the lever 8, and rod 9 provided with the nuts 10 and 11. 60

The numeral 12 designates the hot well provided with the partition 13 located between the tail pipe 5 and the overflow pipe 4, and extended upward to a point above the outlets of each of said pipes; and the hot 65 well is provided with a common form of overflow pipe 14, all of these parts being of any ordinary or preferred form of construction.

The tail pipe 5 is connected with the condenser body by a pipe section 15 which is preferably provided with an enlarged flange 16 at its upper end, said flange being of the same diameter as the lower flanged end 17 of the condenser body to which it is secured 75 by bolts or any suitable or preferred fastening means.

Between the flanges 16 and 17 is clamped the annular plate 18, and between said plate and said flange 16 a space is provided, as at 80 19, preferably by recessing either said flange 16 or plate 18, or both, Fig. 1 of the drawings showing the flange 16 as recessed.

Secured in plate 18 and extending up under the umbrella are one or more open 85 ended pipes 20 which afford a free communication between the interior of the body of the condenser under the umbrella through space 19 to the tail pipe 5.

Seated upon the recessed edge of the aperture in plate 18 is a bushing 21 which is preferably beveled backwardly and downwardly, its upper surface being retained flat in order that the water flowing out of the condenser may be compelled to assume a decided curve, 95 as indicated in dotted lines by Fig. 1 of the drawings thereby insuring a good sized *vena contracta* being formed.

The modification shown by Fig. 2 of the drawings is in all substantial particulars the 100 same as the preferred form disclosed by Fig. 1, with the exception that the flange 160 of the pipe section 150 is not recessed as is the flange 16 in Fig. 1, a space 210 being formed

between two bottoms 211 and 212 of the condenser body 100, a pipe 213 being provided which communicates with this space 210 from the outside of the condenser, but either 5 this pipe or a continuation thereof extends into the condenser and opens under the umbrella in the same manner as pipes 20 shown by Fig. 1.

In the construction shown by Fig. 2, the 10 aperture 214 through the uppermost bottom of the condenser is provided with a perpendicular boundary, while the aperture 215 provided through the lowermost bottom is provided with a downwardly and inwardly flaring periphery.

The modification shown by Fig. 3 of the drawings is substantially the same in structure as the two forms of condenser already described, with the exception that the condenser body 1000 is provided at its lower end 20 with two bottoms 1001, 1002, and that the pipe section 1500 is preferably made integral with the lowermost bottom 1002 and extends up within the space 2100 between the two 25 bottoms nearly to the uppermost bottom 1001, this space being in open communication with the overflow pipe 400, through which free communication is afforded between the interior of the body of the condenser and the tail pipe 5. The uppermost bottom 1001 is provided with an aperture 1003 disposed immediately above the upper open end of pipe section 1500 and coaxial therewith, the periphery of said aperture 30 being preferably beveled outwardly and downwardly, substantially as shown by Fig. 35 of the drawings.

The operation of each of the three forms of apparatus disclosed is similar. Steam or 40 other fluid to be condensed being admitted through aperture 2, condensing water being admitted through pipe 3 and sprayed over umbrella 6 in the usual way, the steam or fluid will be condensed and the condensing 45 water and the water of condensation will flow out through tail pipe 5 into the hot well 12, but in flowing over the bushing 21 or through the apertures 214 or 1003, the compact stream of water will be reduced in sections 50 at the passageways and will form the well known *vena contracta* with the space about which either the pipes 20 or pipe 213 or the overflow pipe 400 afford free communication. Owing to the high vacuum created 55 by the *vena contracta*, the air and uncondensable gases in the condenser body will flow in a steady uninterrupted stream into said space of high vacuum, the air when it enters said space being removed by the aspirating 60 effect of the flowing body of water.

What I claim is,—

1. The combination with a condenser body, of a tail pipe leading therefrom, said

condenser body being formed adjacent said tail pipe so that the water will flow therefrom at an angle to the flow in the tail pipe whereby a contraction of the vein or *vena contracta* is formed, and a pipe freely communicating with the interior of said condenser body and with the space about said 65 70 *vena contracta*.

2. The combination in a condenser, of a body provided with steam and water inlets and an umbrella and a tail pipe, said body being formed adjacent said tail pipe so that 75 water will flow therefrom at an angle to the flow in the tail pipe whereby a contraction of the vein or *vena contracta* is formed, and a pipe affording free communication between 80 the space within the body beneath said umbrella and the space about said *vena contracta*.

3. The combination in a condenser, of a body provided with steam and water inlets and a tail pipe, of a pipe affording communication between the interior of said condenser body and said tail pipe for the removal of air 85 from said condenser body, said pipe being so positioned that it is normally surrounded by the water in the condenser body.

4. The combination in a condenser, of a body provided with steam and water inlets, a tail pipe and an umbrella, of a pipe affording communication between the space within the body below said umbrella and said tail 95 pipe for removing air from said body, said pipe being so placed that it is surrounded by the water contained in the body of the condenser.

5. The combination in a condenser, of a body provided with steam and water inlets, an umbrella and a tail pipe, said tail pipe being provided with a section having an enlarged recessed flange, and an apertured plate secured between said body and said recessed flange and provided with a pipe extended up beneath said umbrella.

6. The combination in a condenser, of a body provided with steam and water inlets, an umbrella and a tail pipe, said tail pipe being provided with a section having an enlarged recessed flange, an apertured plate secured between said body and said recessed flange and provided with a pipe extended up beneath said umbrella, and a bushing in the aperture of said plate.

7. The combination in a condenser, of a body provided with steam and water inlets, and a tail pipe, said tail pipe being provided with a section having a flange, an apertured plate secured between said body and said flange, one of said parts, namely said flange and said plate, being recessed, and a conduit connecting said recess and said body.

8. The combination of a condenser body, water and steam inlets thereto and a tail pipe 125 leading therefrom, the body interior surfaces

about the tail pipe being at an angle to interior surfaces of the tail pipe whereby a volume of water flowing from said body into said tail pipe will assume a contracted vein, and
5 means of free communication between the said body and the space about said contracted vein.

In testimony whereof, I affix my signature in the presence of two witnesses.

ROYAL D. TOMLINSON.
